UNITED STATES PATENT OFFICE

MATTHEW H. OWEN, OF DETROIT, MICHIGAN

BOX CAR DOOR

Application filed September 2, 1930. Serial No. 479,213.

My invention relates to doors and the like and has for one object to provide a new and improved type of door and door closing, locking and supporting means applicable to doors for railroad box cars, warehouses, refrigerators and the like.

Primarily, my invention is intended to solve a very serious problem in connection with doors such as railroad box car doors where it is necessary when the door is closed to provide positive means to prevent the entrance of dust, dirt and rain and to provide means making it impossible for the car door to be pried open even for a short distance, as it can with conventional door locking means where small boxes can be removed from the car without mutilating the lock and seal. My invention is to provide a closure and locking device wherein the door cannot be moved away from the wall or the door aperture without destruction of the seal. My invention is illustrated as applied to a railroad box car, more or less diagrammatically in the accompanying drawings wherein;

Figure 1 shows the door in the closed position;

Fig. 2 shows the door in open position;

Fig. 3 is a section on an enlarged scale along the line 3—3 of Fig. 1;

Fig. 4 is a section on a further enlarged scale along the line 4—4 of Fig. 2;

Fig. 5 is a section on an enlarged scale along the line 5—5 of Fig. 1;

Fig. 6 is a section on an enlarged scale along the line 6—6 of Fig. 1.

A is the supporting frame of a box car carrying a floor A¹ above which rise supporting stringers A² to support a roof, A³. Siding A⁴ is carried by the stringers A² on the side therefor, and there is a door opening as indicated at A⁵ in Figure 2. This door opening is provided at the top with a lintel A⁶ which projects outwardly from the sheathing A⁴ slightly beyond the stringers A².

Bolted or screwed to the siding A⁴ immediately above the lintel A⁶ is a track B. This track has its inner flange bolted or screwed to the siding A⁴. This track resting on the top 50 of the lintel extends outwardly therebeyond

and the flange B¹ overhangs the lintel, there being a sufficient clearance between the flange and the lintel for the door B² which may be of wood or metal or a composite as the case may be. B³ is a hanger extending upwardly from the door enclosing the flange B¹ overlying the outer edge of the track B and carrying a plurality of rollers B⁴ which engage such track so as to provide a roller support from which the door hangs, no special track being needed, and thus a positive interlock is provided throughout the entire extent of the top of the door between the door and the lintel and also providing a water-tight closure between the lintel and the door top.

C is a front door jam projecting outwardly from the siding a distance substantially equal to the lintel and reinforced by means of a Z-bar C¹. The lintel C² on the side adjacent the door projects similarly to the lintel C and is similarly reinforced by a Z-bar C³. Projecting outwardly from the lintel C and overhanging it is an angle bar C⁴ having a flange C⁵ spaced from the jam C sufficiently to permit the door B² to enter the space between it and the jam thereby providing along the front edge of the door a positive interlock from top to bottom as well as a water proof closure. C⁶ are the usual brackets projecting upwardly from the car well spaced therefrom to permit passage of the door as it slides into and out of register with the door open and adapted to hold the door at all times in proper position. These brackets take the form of short Z-bar elements extending along the entire path of travel of the door just as does the door B. C⁷ is the usual handle at the bottom of the door by which the door may be opened or closed.

D is a hinge plate rigidly attached to the outside of the Z-bar carrying a hinge pin D¹ spaced within the contour of the jam and thus behind the door B² in all positions. Pivoted on this pin D¹ is an angle bar D² which, in the position shown in Figure 3, encloses the rear edge of the door forming a positive interlock between it and the car body and providing a watertight closure and when in the retracted position shown in Figure 4 being back out of the way so that the door

may be withdrawn. D³ is a strap bolted or riveted to the siding and having pivoted thereon a link D⁴ which terminates in an eyelet D⁵ adapted to be engaged by the lock pin D⁶ slidable in the staple D⁷ on the pivoted angle bar or locking jam D². This pin D⁶ is slotted at D⁸ to take the usual car seal D⁹ which insures that the parts remain in locked position until the seal is destroyed because without its destruction the pin D⁶ cannot be withdrawn. As long as the pin D⁹ is not withdrawn the member D⁴ acts as a strut or brace holding the jam D² in the position shown in Figure 3 and closing the rearmost edge of the door to positively prevent travel or longitudinal movement of the door as this cannot take place without destruction of the lock which owing to its great weight and strength is exceedingly difficult. If this lock is applied to a car of the outside sheathed type then the sheathing will be cut away to form a pocket to contain the members D², D³ and D⁴. Aside from that the locking action will be substantially the same. In order to hold the door in the open position when that is desired the anchor plate E is provided on the jam C². Pivoted on this anchor plate is a link E¹ and pivoted on it is a hasp link E² which hasp link is provided with an eyelet E³ adapted when shown in the position in Figure 2, to be interlocked with the hasp E⁴. The locking pin E⁵ locks the car in open position and prevents its being shaken out of place when the car is moved when the door is open.

I claim:—

In combination with a box car and sliding door therefor, means for holding the door in position spaced from the outer wall of the car, a lock for the door comprising an angle extending substantially the entire height of the door pivoted along a vertical axis and adapted when in the inoperative position to be enclosed between the door and the car, the angle being pivoted to the car immediately behind the door, a lock link pivoted on the car adapted to be enclosed behind the door, the relation between the angle and the link being such that when the door is closed and the angle is rotated into engagement with the rear edge of the door, it overlies the outer wall thereof, and the link being adapted to abut on the angle, means for locking the link and angle in fixed relation to hold the angle against rotation and form a permanent lock for the door.

Signed at Chicago county of Cook and State of Illinois, this 23rd day of July, 1930.

MATTHEW H. OWEN.
